UNITED STATES PATENT OFFICE.

JOHN J. LOW, OF SANTA ANA, CALIFORNIA.

AMPLIFIER FOR RADIOPHONES.

Application filed October 21, 1922. Serial No. 595,834.

To all whom it may concern:

Be it known that I, JOHN J. LOW, a citizen of the United States, residing at Santa Ana, in the county of Orange and State of California, have invented new and useful Improvements in Amplifiers for Radiophones, of which the following is a specification.

My invention relates to amplifiers particularly adapted, although not necessarily, for use in the receiving sets of radiophones to supplant the usual head phones. More particularly, my invention appertains to amplifiers of that type including a permanent magnet and a solenoid which cooperate to effect the vibration of an armature in causing the vibration of a diaphragm.

In amplifiers of this character, there are two objections to their success commercially: first, the countercurrents set up in the solenoid because of the magnetic lines of force emanating from the permanent magnet and traversing the solenoid winding affect the armature to the extent of producing that familiar and objectionable roaring sound at the diaphragm which is such a hindrance to the clarity of the sounds produced. The second objection is the rigid connection between the diaphragm and armature which functions to cause an early disintegration of the mica diaphragm, and which prevents the control of the volume of sound produced to render it applicable to private as well as public use.

It is a purpose of my invention to provide an amplifier which overcomes the above pointed out objections.

I will describe one form of amplifier embodying my invention and will then point out the novel features thereof in claims.

40 In the accompanying drawings,

Figure 1 is a view showing in vertical section one form of amplifier embodying my invention;

Figure 2 is a plan view of the amplifier mechanism removed from the casing shown in Figure 1;

Figure 3 is a view showing in side elevation the mechanism shown in Figure 1;

Figure 4 is a sectional view taken on the line 4-4 of Figure 2;

Figure 5 is a fragmentary enlarged detail perspective view of the pole pieces of the permanent magnet and the adjacent mechanism.

55 Similar reference characters refer to similar parts in each of the views.

Referring specifically to the drawings, and particularly to Figure 1, my invention, in its present embodiment, comprises a casing or housing 15 constructed of non-magnetic material and provided with a cover 16 of similar material formed with an opening adapted to receive an ear piece 17. The opening of the cover 16 receives a diaphragm 18 held in place by the ear piece and operatively connected to an armature 19 of a solenoid contained within the casing 15. The solenoid includes a winding 20 supported on a core 21 of insulating material which is engaged by set screws 22 at its far corners for centering the armature with respect to the pole pieces of the permanent magnet. The permanent magnet is indicated at 23 and as shown in Figure 1 is mounted within the casing 15. The pole pieces designated 24 are constructed in the manner clearly shown in Figure 5, wherein it will be seen that two north poles and two south poles are provided. These poles are disposed in circumferential alignment with the inner and outer peripheries of the permanent magnet 23 so that the gaps between the poles are adapted to receive the opposite ends of the armature 19. The armature 19 is fulcrumed on pins 25 so as to allow of a rocking movement of the armature within the core 21. The armature 19 is formed of a rapidly demagnetizable material, and because of its association with the solenoid winding 20 it will be clear that polarities are established in the armature to cooperate with the polarities of the pole pieces 24 in effecting the vibration of the armature about the pivot pins 25 as a center. The mode of operation of an amplifier of this character is well known in the art.

In the assembly of the solenoid between the ends of the permanent magnets 23, a rectangular casing 26 of diamagnetic material is arranged between the pole pieces 24 and in embracing relation to the core 21, the screw 22 extending through the casing 26 and engaging the core for properly centering the latter and, consequently, the armature with relation to the pole pieces of the permanent magnet. The upper screws 22 project through the cover 16, as clearly shown in Figure 2.

From the foregoing arrangement of the casing 26 and the fact that it is formed of diamagnetic material, it will be clear that it operates to prevent the passage of the

magnetic lines of force emanating from the permanent magnet 23 through the turns of the solenoid winding 20, thereby precluding the generation of counter currents in the solenoid. The magnetic flux of the solenoid winding 20 is thus free to properly act upon the armature 19 and to cooperate with the flux of the permanent magnet in effecting the proper vibration of the armature. The net result is that the armature acts in such a manner as to effect a vibration of the diaphragm 18 without the usual roaring sound so common in similar amplifiers heretofore proposed.

15 The armature 19 is operatively connected with the diaphragm 18 through the medium of a lever 27 having one end bent at an angle to provide an extension 28 which is connected to the center of the diaphragm through the medium of a screw 29. The opposite end of the lever 27 is connected to a link 30 which, in turn, is connected to an extension 31 of the inner end of the armature 19. The lever 27 is supported for rocking movement by means of a cross arm 32 formed integral with the lever and provided with grooves adapted to receive the edges of blades 33 secured in projections 34 forming a part of the cover 16. The cross arm 32 is urged in the direction of the blades 33 by means of springs 35 mounted on the shanks of screws 36 threadedly engaging the projections 34 so as to be capable of adjustment for bearing the pressure exerted by the springs.

20 In practice, the lever 27 under the vibratory action of the armature 19 oscillates about the edges of the blades 33 as a center, and because of the small bearing surface between the cross arm 32 and the blades 33, it will be evident that the lever 27 is extremely sensitive to the movement of the armature in transmitting such movement to the diaphragm 18.

25 To control the volume of sound produced by the diaphragm 18 so as to render the amplifier applicable to private as well as public use, the oscillatory movement of the lever 27 can be readily controlled by an adjustment of the screws 36 to increase or decrease the urging action of the springs 35 with regard to the cross arm 32. For example, if

it is desired to modulate the sounds emanating from the diaphragm 18, the screws 36 are screwed inwardly with respect to the projections 34 to compress the springs 35 so as to oppose movement of the cross arm 32, thereby providing a substantially rigid connection between the armature and the diaphragm.

30 I claim as my invention:

1. An amplifier of the character described, comprising a source of magnetism of constant flux density, a second source of magnetism of varying flux density, an armature operable by the sources of magnetism, a casing 65 of diamagnetic material for preventing the first source of magnetism setting up counter-currents in the second source of magnetism, a diaphragm operable by the armature, and adjustable means for operatively connecting 70 the armature and diaphragm for varying the intensity of the vibrations transmitted to the diaphragm from the armature.

2. In an amplifier of the character described, a permanent magnet having pole 75 pieces arranged in pairs with the pole pieces of one pair spaced from the pole pieces of the other pair, an electro-magnet arranged between the two pairs of pole pieces, an armature pivotally sustained on the electro-magnet and operating between the pole pieces, and a casing of diamagnetic material surrounding the electro-magnet between the pairs of pole pieces for the purpose described.

3. In an amplifier of the character described, a permanent magnet having pole pieces arranged in pairs with the pole pieces of one pair spaced from the pole pieces of the other pair, an electro-magnet arranged 90 between the two pairs of pole pieces, an armature pivotally sustained on the electro-magnet and operating between the pole pieces, a casing of diamagnetic material surrounding the electro-magnet between the 95 pairs of pole pieces for the purpose described, and means carried by the casing for centering the armature with relation to the pole pieces.

In testimony whereof I have signed my 100 name to this specification.

JOHN J. LOW.
